COMBINED RECORD MATERIAL REWIND UNIT AND ADDING MACHINE OR SIMILAR ARTICLE

Pierre L. Crease, Kettering, Ohio, assignor to The National Cash Register Company, Dayton, Ohio, a corporation of Maryland

Filed Jan. 31, 1969, Ser. No. 15,626

Term of patent 14 years

Int. Cl. D18—01

U.S. Cl. D64—11

FIG. 1

Des. 216,340

PAGE 2

FIG. 2

FIG. 3

FIG. 4

FIG. 5

FIG. 1 is a front perspective view of a combined record material rewind unit and adding machine or similar article showing my new design;

FIG. 2 is a rear perspective view thereof;

FIG. 3 is a right side elevational view;

FIG. 4 is a left side elevational view; and

FIG. 5 is a rear elevational view thereof.

The dominant feature of my design resides in the combination with an adding machine or similar article of a record material rewind unit characterized by a pair of substantially vertical arm members inclined slightly rearwardly and extending upwardly in spaced, parallel relationship adjacent either side of the record material supply well of the adding machine or similar article and a substantially horizontal record material rewind spool extending therebetween in spaced relationship above the supply well, the one arm member being substantially planar and uniform in thickness throughout and the other arm member being of a thickness greater than that of the one

arm member and having a cylindrical portion of a thickness likewise greater than that of the one arm member extending outwardly therefrom in substantial axial alignment with the record material rewind spool, as shown.

I claim:

The ornamental design for a combined record material rewind unit and adding machine or similar article, substantially as shown and described.
